UNITED STATES PATENT OFFICE.

CHARLES LOUIS TANNER, OF MERTON, ENGLAND.

TYPEWRITER.

1,409,620.

Specification of Letters Patent. Patented Mar. 14, 1922.

Application filed February 7, 1920. Serial No. 356,942.

(GRANTED UNDER THE PROVISIONS OF THE ACT OF MARCH 3, 1921, 41 STAT. L. 1313.)

To all whom it may concern:

Be it known that I, CHARLES LOUIS TANNER, a subject of the King of Great Britain and Ireland, and a resident of Merton, 5 county of Surrey, England, have invented a certain new and useful Improvement in Typewriters, (for which I have obtained a patent in Great Britain, No. 124,881, dated 3d April, 1918,) of which the following is 10 a specification.

My invention relates to typewriters of the kind in which the material to be typed on is moved transversely of the machine when typing, is carried in a vertical position, and 15 is shifted vertically for line spacing.

My invention has for its object the improved construction, combination and arrangement of a machine of the above nature which will enable a ledger, book, pad, or the 20 like to be typed on.

For a clear understanding of the invention, reference is to be had to the following description and accompanying sheets of drawings, wherein:—

25 Figure 1 is a longitudinal sectional view of a machine constructed in accordance with the invention, but with ribbon mechanism omitted.

Figure 2 is a front view of the machine.

30 Figure 3 is a front view of the skeleton frame platen, shown detached.

Figure 4 is a plan view of the carriage end of the machine.

Like letters of reference indicate corresponding parts in the several figures.

In carrying out my invention, and referring to the drawings, behind that part *a* of the machine frame carrying the type bars *b*, only one of which is shown in the drawings, 40 and the ribbon mechanism *c* (which type bars *b* have an upward and forward movement imparted to them by an arrangement of levers, links and keys *b*¹, *b*², *b*³) there is provided a vertically disposed skeleton frame or carriage *d*, *d*¹, slidably mounted on, so as to be traversed along, a horizontal and transversely disposed bar *d*², fixedly carried by brackets *d*³ on transversely disposed track plate *d*⁵ on the base *a*¹ of the machine. 45

50 and supported by means of rollers *d*⁴ which bear on the transversely disposed plate *d*⁵ on said base *a*¹, said rollers *d*⁴ being carried by the lower part of the carriage *d*, *d*¹.

The carriage *d*, *d*¹, at each end, and towards the top thereof, is provided with

rollers *d*⁶ which take on a transversely disposed flat bar *e* attached to the machine frame *a* to guide and support the carriage *d*, *d*¹.

The ends of the carriage *d*, *d*¹ are constituted by vertically disposed grooves or guideways *f* for the reception therebetween of a flat and skeleton frame platen *g*, which platen *g* in turn is provided with vertical end grooves or guideways *g*¹ for the reception 60 therein of the edges of an open book *g*², as shown in Figure 2, or a pad *g*³, as shown in Figure 1, which is slid downwards on the platen *g* till stopped by engaging in a hook-shaped ledge *g*⁴ on the bottom end 65 of the platen *g*.

The leaves of the book *g*² are maintained flat by the edges of the grooves or guideways *g*¹ of the platen *g*, and by a flat bar *h*, Figure 2, which engages by its upper end 70 in a slot *h*¹ of a slotted and hinged gate *h*² in the hook-shaped ledge *g*⁴ on the top of the platen frame *g*, and by its lower end in one of two slots *h*³ in the hook-shaped 75 ledge *g*⁴ on the bottom end of said platen frame *g*, the bar *h* being shifted to the one or the other side of the centre of the book *g*², according to which side of the book is to be typed on, said book being held against the flat bar *h* and the edges of the grooves or guideways *g*¹ by means of blade springs *i*, which springs *i* are attached to the skeleton 80 framed platen *g*.

The carriage *d*, *d*¹ which is connected to the spacer rack *i*², is released by the movement of the space key *i*³ which, through rock bar *i*⁴, actuates the detents *i*⁵ which engage the ratchet wheel *i*⁶, the carriage *d*, *d*¹ being drawn along in known manner, and a column-finder release key, not shown in the 85 drawings, is arranged on the left side of the machine frame.

To effect the vertical movement of the book, pad or the like, i. e. line spacing, the right hand edge of the platen frame *g* is provided with a vertically disposed line spacer rack *g*⁵, with which engages the spring-controlled pawl *g*⁶ pivotally mounted on a bracket *j* forming part of the frame of the carriage *d*, *d*¹, a spring-controlled detent or pawl *g*⁷ pivotally mounted on the downwardly extending portion *j*¹ of the bracket *j* on the frame of the carriage, engaging in said line spacer rack *g*⁵, preventing 90 downward movement of the platen *g*.

till said detent or pawl g^8 is released by hand.

The left hand groove or guideway g^1 of the platen g is made adjustable, for instance, by slots and grooves g^* , so that it may be moved away from or towards the other groove or guideway of the platen, to accommodate various sized books, pads or the like.

10 I claim:—

In a typewriter, a carriage slidably mounted on the base frame of the machine and having vertical guide-ways, a horizontally disposed guide rail, rollers carried by the

carriage and engaging said rail, a frame 15 platen slidably mounted in the said guide-ways and having vertical grooves for receiving an article to be written upon, one of the grooves being adjustable, a hook shaped slotted ledge at the bottom of the platen, a 20 hinged and slotted gate at the top thereof, a bar for engaging with said ledge and gate, and means associated with the platen for effecting line spacing.

In testimony whereof I have affixed my 25 signature hereto this 30th day of December, 1919.

CHARLES LOUIS TANNER
